F. H. Gibney.

Des. 1657

I, J. H. Gibney, of New York, N.Y.
Dellers Patent No. 1657, dated Sept. 23, 1862,

The schedule referred to in these Letters Patent and making part of the same,
To all whom it may concern:

Be it known that I, J. H. Gibney, of the City, County, and State of New York, have produced a new and ornamental design for Fork and Spoon Handle; and I do hereby declare that the following is a full, clear and exact description of the same, reference being had to the accompanying drawing forming a part of this specification, in which

Figure 1. represents a plan or top view of a fork

ornamented with my design.

Figure 2. is a plan of the underside of the same.

Similar letters of reference in both views indicate corresponding parts.

My design has reference to the outward form or shape of a handle for spoons and forks, and to the various mouldings and ornaments on the upper and on the lower side of said handle.

The outer end of the handle A, consists of an oblong oval a, a small portion of which is cut away or concealed by a circular shield b, from which the shaft c, extends to the prong end of the fork, or to the bowl of the spoon.

The oval a, is bordered on the upper side of the handle by two ridges d, d' which is separated by an oval shaped groove e. An arabesque f, extends from that part of the groove e, next to the outer end of the handle A, through the inner ridge d', and a short distance within the smooth inner field of the oval a.

The circular shield b, is provided on the upper side of the handle with a flat border g, from which a high semi circular projection h, rises into the inner smooth field of the oval a. The border g, surrounds an arabesque i, which covers nearly the whole inner field of the shield b, and from which a branch extends over the middle of that part of the shaft c, which adjoins the shield b.

The shaft c, is ornamented on its upper side by a border k, consisting of two small ridges which are separated from each other by a narrow depression, and which at that end where the shaft joins the body of the fork or spoon, are curved in the shape of a heart which is further ornamented by a small arabesque l, rising from the central bend of said heart shaped curve between the borders of the shaft.

The underside of the oval a, is bordered by two ridges m, m', separated from each other by a groove n, similar to the border d, d', e, on the upper side, but instead of the arabesque f, the ridge m', is bent in, so as to form two semi circles o, which are joined by a right line p.

Dec. 1657

The border g of the shield b, is similar on the under side of the handle to that on the upper side, but the arabesque g, which occupies a portion of the inner field of said shield is smaller than the corresponding arabesque on the upper side and its point does not extend on the shaft.

The under side of the shaft is bordered on each side by two small ridges x. x', separated from each other by a narrow depression s, similar to the border k, on the upper side of said shaft.

The outer ridges x vanish on the edge of the prong end of the fork or bowl end of the spoon, and the inner ridges spread to a flat pear shaped border t, which extends over the under side of the body of the fork, or bowl of the spoon, and which surrounds a space u, that is ornamented by an arabesque v. - That part of the shaft c, which is inclosed between the ridges x' on the under side, is depressed, and the corresponding part, between the border k, on the upper side of the shaft is raised.

The whole handle, with the fork or spoon, when cast of silver, or made of any other rich and suitable material, and properly finished, presents a highly ornamental appearance.

Having thus fully described my design, what I claim as new, and desire to secure by Letters Patent, is -

The oval a, ornamented with ridges d, d', groove e, and arabesque f, on the upper, and with ridges m, m', groove n, and curve o, p, on the under side, - also the shield b, ornamented on the upper side with border g, and arabesque i, and on the under side with border g', and arabesque g. Also the shaft c, ornamented on the upper side with a border k, and arabesque l, and on the under side with ridges x, x', pear shaped border t, and arabesque v, all as arranged and shown to form a spoon or fork handle as described.
